UNITED STATES PATENT OFFICE.

EDWARD M. SANDERS, OF CONCORD, NEW HAMPSHIRE.

CAMP-STOVE.

SPECIFICATION forming part of Letters Patent No. 309,565, dated December 23, 1884.

Application filed January 30, 1884. (No model.)

To all whom it may concern:

Be it known that I, EDWARD M. SANDERS, a citizen of the United States, residing at Concord, in the county of Merrimack and State 5 of New Hampshire, have invented a certain new, useful, and Improved Camp-Stove; and I hereby declare the following to be a clear and exact description thereof.

The object of my invention is to supply a 10 portable stove which may be readily taken apart and placed in a small box, of paste-board or other cheap material, of such size or dimensions as will enable a laboring man to carry the same to and from his work without 15 inconvenience.

By reference to the accompanying drawings, forming part of this specification, in which similar letters of reference indicate corresponding parts in all the figures, the nature of my 20 invention and the manner of constructing the same will be more clearly seen.

Figure 1 is a front elevation of my improved stove. Fig. 2 is a side view. Fig. 3 represents a sectional plan view. Fig. 4 is a cross- 25 section taken on line Y Y of Fig. 3, showing the back part up to said cutting-line.

The entire stove is composed of thin sheet-iron, such as is ordinarily used for stove pipes and elbows. The side edges of the bottom A 30 form the single groove a, as is shown best in Fig. 4, and the back edge, a', is bent up at a right angle, as is shown in Fig. 2, by which means the sides and back of the stove are partially held in place, as will be subsequently 35 explained. The sides B B, when formed ready for use, may be compared to a shallow pan having open corners, all four edges, b, being bent over to a right angle. The back C has a pipe-hole, c, into which a thimble, D, is in- 40 serted from the inside and fastened thereto by means of rivets, which pass through the flange d and the said sheet-iron back C; or a short piece of pipe, D', one inch (more or less) in length, may be fitted to the thimble D and 45 riveted thereto, which will obviate the necessity of rivets in the flange d. A damper, E, may be placed either in the short pipe D' or in the thimble D, which is shown in Figs. 2 and 4. The top edge of the back C is bent 50 at right angles outward, and the bottom edge is bent at right angles inward. The front F of my improved stove is formed in a similar manner, excepting that in place of the pipe-hole c there is a smaller hole, f, located at 55 such a point as will give the stove proper

draft, and a pivoted cover, f', is provided to close the same when desired. The side edges of the top G form the grooves g in the same manner as do those of the bottom A; but the front and back edges are left perfectly flat. 60 A round hole, g', is made in the top G for the purpose of feeding the stove, and the cover H is simply a piece of sheet-iron cut round, and of sufficient size to cover said hole. Wire hooks I may be riveted to the sides B B, and 65 when the stove is put together ready for use these hooks I will enter holes J, made in and through the flanges of the sides B B, which come in contact with the front and back of the stove, and thence through said front F 70 and back C, thus holding or fastening the sides to the back and front of the stove in a simple and handy manner.

A stove constructed in the manner described will be found a very handy article by men 75 who have to go a long distance from home to their daily labor—such, for instance, as quarrymen, lumbermen, or even hunters.

The stove should be about seven inches square and about five inches in height, and 80 a few twigs or a little shavings will be all the fuel required to heat the contents of a man's dinner-pail; and before leaving for home, by simply slipping the wire hooks I, the stove will all fall to pieces, when the ashes may be 85 shaken off, and the different parts may be piled one above the other and be placed with two lengths of pipe in a cheaply-made paste-board box between four and five inches high, and carried by a workman to and from his 90 home without inconvenience. The right-angle bends given to the top and bottom edges of the front E and the back C serve to stiffen the said parts, and also to prevent the escape of ashes, smoke, or heat, but are by no 95 means essential to the perfect operation of the stove.

Having described my invention, what I claim, and desire to secure by Letters Patent of the United States, is—

A portable camp-stove constructed of thin sheet-iron, substantially as described, having joints composed of the single grooves a g and right angles a' b, hooks I, damper E, draft F, and feed-hole g', all constructed and operating 105 as and for the purpose set forth.

EDWARD M. SANDERS.
